BIDET TOILET SEAT

Michael F. Slawinski, 12911 S. Parnell Ave., Chicago, Ill.
60628, and Joseph J. Cykowski, 12412 S. Carpenter,
Calumet Park, Ill. 60643

Filed Dec. 26, 1973, Ser. No. 427,566

Term of patent 14 years

Int. Cl. D23—02

U.S. Cl. D23—71

FIG-2.

FIG-3.

FIG. 4.

FIG. 5.

FIG. 6.

FIG. 7.

7-25-9.

7-25-10.

FIG. 11.FIG. 12.FIG. 13.FIG. 14.

FIG. 1 is a perspective view of a bidet toilet seat showing our new design;

FIG. 2 is a front elevational view thereof;

FIG. 3 is a top plan view thereof;

FIG. 4 is a bottom plan view thereof;

FIG. 5 is a rear elevational view thereof;

FIG. 6 is an elevational view taken from one side thereof;

FIG. 7 is an elevational view taken from the side opposite that shown in FIG. 6;

FIG. 8 is a perspective view of a modified form of the bidet toilet seat shown in FIG. 1;

FIG. 9 is a front elevational view of FIG. 8;

FIG. 10 is a top plan view of FIG. 8;

FIG. 11 is a bottom plan view of FIG. 8;

FIG. 12 is a rear elevational view of FIG. 8;

FIG. 13 is an elevational view taken from one side of FIG. 8; and

FIG. 14 is an elevational view taken from the side opposite that shown in FIG. 13.

The fragmentary broken line representation of a water line in FIGS. 1, 3, 4, 5, 6, 8, 10, 11, 12 and 13 and a cover in FIGS. 1 and 8 are for purposes of illustration only.

We claim:

The ornamental design for a bidet toilet seat, substantially as shown and described.
